UNITED STATES PATENT OFFICE.

JOHN H. B. BRYAN, OF PHILADELPHIA, PENNSYLVANIA, ASSIGNOR OF ONE-HALF TO CHARLES T. THOMPSON, OF SAME PLACE.

TOY BOWLING-ALLEY.

SPECIFICATION forming part of Letters Patent No. 242,187, dated May 31, 1881.

Application filed April 2, 1881. (No model.)

To all whom it may concern:

Be it known that I, JOHN H. B. BRYAN, of Philadelphia, in the county of Philadelphia and State of Pennsylvania, have invented certain new and useful Improvements in an Amusing Toy in the Nature of a Miniature Bowling-Alley; and I do hereby declare that the following is a full, clear, and exact description of the invention, which will enable others skilled in the art to which it appertains to make and use the same, reference being had to the accompanying drawings, which form a part of this specification.

The object of my invention is to furnish a new and useful and innocent game of skill; and to that end the invention is based on a combination of simple and well-known mechanical principles, so arranged as to produce an amusing toy in the nature of a miniature bowling-alley of convenient size and shape for play-room or parlor.

In the drawings, Figure 1 is a side view of the entire toy, parts being broken away where necessary. Fig. 2 is a view of the front.

A is a narrow box or trough of greater length than width, made of suitable materials, provided with an inclined bottom divided by cross-bars into several parts or pockets.

A bar, B, having its upper edge narrow and straight, is so hung on a cross-bar at C as to afford the handle end D considerable vertical and lateral play, so that at the pleasure of the operator the smooth upper surface may be made an inclined plane of variable angle. At the end of the bar B, beyond the bearing, is fixed a target, E, with its surface parallel to the upper sides of the box A. This target forms a part of a trigger designed to engage with the slide F when locked in the position shown in Fig. 2. The locking device consists of a catch-pin, L, on the front face of the frame, adapted to engage a corresponding notch on the slide F. The springs K K press the slide slightly against the face of the frame, and when the slide is down the lower point of the target-trigger is held by the slide perpendicularly, the target part F being horizontal. When the projectile falls on E the lower vertical part of the trigger acts as a lever to force the slide away from the catch-pin L, and the slide F is thus released and flies up. This locking arrangement is subject to variation, and the point of the target-trigger may be turned up and the

slide locked from above the trigger to quite as good advantage as in the manner here shown. 55

F is a slide, having a vertical movement in suitable guides on the frame of the box, and provided with suitable wire or rubber springs for raising it to the elevated position shown in Fig. 1 when the trigger is struck. 60

On the frame of the box A a bell, H, is fixed, and on the slide F a hammer, I, is placed, adjusted so as to strike the bell and ring it when the slide is released and flies up.

The front side of the slide toward the operator may be ornamented by a picture or other object, which is concealed when the slide is down and exposed when it is up. 65

The operation of this device is as follows: The slide being up, as in Fig. 1, the hand is 70 placed on its top and it is pressed down and locked, as in Fig. 2. The object of the game is to cause a small cylinder of metal, G, or a marble, to roll down the entire length of the narrow upper surface of the bar B and fall upon 75 the target E, thereby releasing the slide F, and causing it to fly up and expose the ornament on its front, and at the same time ring the bell. As the bar B has a movement in every direction, care must be taken by the player to adjust its surface so that the roller will keep to it and not fall off till it reaches the target. The highest number of points to be scored are 80 counted upon thus reaching the target. If the roll falls off short of this, it goes into one of the 85 pockets in the bottom of the box, and points are scored increasing in value as they near the goal.

Having thus described my invention, what I claim as new, and desire to secure by Letters 90 Patent, is—

1. A toy game of skill, consisting, essentially, of a variably-adjustable inclined plane, a target-trigger adapted to release a vertically-movable slide, and a suitable projectile, substantially as described. 95

2. The combination of the adjustable inclined plane B, the projectile, the target E, and slide F, substantially as described.

In testimony that I claim the foregoing as 100 my own I have hereto affixed my signature in presence of two witnesses.

JOHN H. B. BRYAN.
